DRIVING AND CONTROL MECHANISM FOR
TURRETS

Benjamin Norton Foster, Keene, N. H., and
Frank L. Fisher, Wauwatosa, Wis.; said Fisher
assignor to Allen-Bradley Company, Milwau-
kee, Wis., a corporation of Wisconsin

Application March 11, 1938, Serial No. 195,402

14 Claims.

(Cl. 29—50)

This invention relates to driving mechanisms and controls for turrets and like apparatus such as used in metal working machines of the type wherein work is carried by the turret to be cyclically presented to a succession of power driven tools. Examples of this type of machine are illustrated in United States Letters Patent No. 1,975,005 and No. 2,011,487, issued to E. J. Kingsbury et al., September 25, 1934, and August 13, 1935, respectively.

The primary object of this invention is to provide an improved manner of driving and indexing the turret.

More specifically it is an object of this invention to provide a completely electrical driving and control system for indexing turrets and like apparatus wherein the advance of the turret and also its securing at indexing positions is accomplished by a single electric motor.

Another object of this invention is to provide means whereby the turret is held in an indexing position by the torque of its driving motor.

Another object of this invention is to provide a novel manner of reducing the potential across the driving motor at the time it functions to hold the turret in an indexing position so that the torque employed for this purpose is less than that which obtains during the advance of the turret.

Another object of this invention resides in the provision of a simple, but effective manner of interlocking the forward and reverse switches which control the connection of the reversible motor with its lines so that closure of the reverse switch cannot take place until the forward switch is completely open and any arc across its contacts ceases.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a diagrammatic illustration of a metal working machine embodying this invention;

Figure 2 is a cross sectional view through Figure 1 on the plane of the line 2—2; and

Figure 3 is a wiring diagram of the complete control system.

Referring now particularly to the accompanying drawings in which like numerals indicate like parts, the numeral 5 designates the base of the machine upon which the turret 6 rotates. Inside the base, which is hollow, is the turret advancing mechanism. This mechanism, in its 10 mechanical aspects, consists of a reversible electric motor 7 drivingly connected through gearing 8 with the turret.

A stiff central column 9 carried by the base supports the turret and extends thereabove to 15 mount a head 10. The head 10 carries a plurality of tool heads 11, only three of which are shown for the sake of simplicity of disclosure. Each tool head includes a motor 12 and a reciprocal quill 13 which carries a tool spindle 14. 20 The tool spindle is driven by the motor, and as will be readily apparent, may have any one of a wide variety of tools attached thereto. In the present instance, two of the spindles carry drills 15 while the third drives a tap 16. 25

The descent of the tools onto the pieces of work W which are clamped to the turret and also their retraction to elevated inoperative positions is effected by cams, motor driven, through clutches which are operated by solenoids. The 30 specific manner in which this mechanism functions, however, forms no part of this invention, and therefore has not been shown, suffice it to say that the solenoids are energized at the dictation of the control system to be hereinafter 35 described.

As will be readily apparent, the function of the turret 6 is to carry the work W cyclically to the successive tools, and to properly position and hold the same stationary while the tools perform their work; and it is to be understood that while in the diagrammatic illustration shown, only three individual tool heads are illustrated, and the turret has only four positions of rest, one to provide for the application of the 45 work W to and its removal from the turret, in actual practice there may be more tool heads and the turret would then have an equivalently greater number of positions of rest.

To insure the turret remaining at a standstill 50 during the work period, each tool head controls a limit switch which is opened as its quill starts its tool feeding stroke and remains open until the quill and its tool is completely returned to its raised inoperative position. All of these limit 55

switches, which hereinafter are collectively designated the A limit switches, (not shown in Figure 1, but illustrated in the wiring diagram) are connected in series.

5 Hence, the circuits controlled thereby are open as long as any one tool is still functioning or returning to its retracted inoperative position; and inasmuch as the circuits controlled by these A limit switches must be closed thereat to effect 10 advance of the turret, it follows that as long as any one tool is still functioning, or has not as yet been fully retracted, advance of the turret cannot take place.

As will be hereinafter more fully described, 15 upon retraction of all of the tools and the consequent closure of all of the A limit switches, the reversible motor 7 is connected with its supply lines for forward rotation to cause a forward indexing motion of the turret.

20 Approximately at the time the turret reaches its next indexing position, a snap switch 17 is actuated to effect certain changes in the control circuits whereby the motor 7 is plugged by being connected with the lines through a reverse switch. The snap switch may be of the Burgess type, but as its specific construction is immaterial, it has been only diagrammatically illustrated.

As shown, the snap switch has a spring projected depressible actuating plunger 18, and the 30 switch is so mounted that its actuator is depressible by an arm 19 carried by a spring pressed plunger 20. The plunger 20 rides on the periphery of a flange 21 moving with the turret and snaps into recesses 22 in the flange as they come 35 opposite the plunger. There is one recess 22 for each indexing position so that the snap switch 17 is actuated to effect the desired plugging as each indexing position is reached; and as the plunger 20 rides out of each recess, the snap switch is 40 actuated in the opposite direction for a purpose to be brought out hereinafter.

Upon plugging of the motor, forward advance of the turret ceases, and inasmuch as the plugging is so timed as to permit the turret to advance 45 slightly beyond its proper indexing positions, it follows that a slight retrograde movement of the turret is necessary in each instance to bring it back to its proper indexing position.

To define these positions, the shoulders 23 50 formed by the abrupt ends of the recesses 22 are engageable with the spring pressed plunger 20. At the time of this engagement, the turret is accurately positioned; and to insure unimpaired accuracy, the shoulders 23 may be provided by 55 hardened inserts 24.

While mere plugging of the motor, if the plugging switch were not opened, would effect the desired retrograde movement of the turret, the fact that the plugging is done on full line voltage 60 makes it undesirable to bring the turret back in this manner. The necessary retrograde movement of the turret should be gentle, and means must be provided for holding the turret against the stationary stop.

65 This invention accomplishes these objects in a simple but effective manner by reducing the potential across the motor the instant that the turret commences its retrograde movement, and for this purpose a plugging relay 25, is provided 70 with its actuator 26 operable through friction means 27 by the motor shaft.

The motor 7 operating in a reverse direction and on low voltage thus brings the turret gently against its stationary stop, and as the low voltage connection to the motor is not broken after

the stop has been engaged, it is evident that the torque of the motor holds the turret in its indexed position.

After the turret has been brought to its indexed position and while it is being held there by the 5 reduced torque of the motor, the tool heads feed their tools to the work and retract them to their inoperative positions, it being remembered that during the time the tools move toward the work and until they return to their inoperative positions, the A limit switches remain open so that the next successive cycle cannot begin until the slowest tool has performed its function and has 10 been returned to inoperative position.

The control system for effecting the sequence 15 of steps as outlined above will now be specifically described, reference being had to the diagram shown in Figure 3.

The main supply lines L¹, L², and L³ which enter at the upper lefthand corner of the diagram 20 are connectible with lines T¹, T², and T³ through an electromagnetic main switch 30. This switch is of the conventional type controlled by "start" and "stop" push buttons 31 and 32.

Deriving energy from the lines T¹, T², and T³ 25 is a transformer 33, the purpose of which is to supply low voltage for operating the motor 7 with reduced torque to impart retrograde movement to the turret and hold the turret against its stop.

Forward operation of the motor 7 is effected 30 upon closure of an electromagnetic forward switch 34, which upon being closed connects the lines T¹, and T³, respectively, with the terminals 1, and 3 of the motor. The manner in which this power circuit is established is clearly traceable on the 35 diagram. It is desired to note, however, that line T² is connected directly with the terminal 2 of the motor and that only the lines T¹ and T³ are broken at the switch 34.

With the motor operating in a forward direction, plugging thereof results from closure of an electromagnetic plugging or reverse switch 35. Upon closure of this switch, the connections to the motor are reversed, that is, the line T¹ is now connected with terminal 3 of the motor, and the 45 line T³ is connected with terminal 1 of the motor.

After plugging of the motor by closure of the switch 35, it is desirable to reduce the potential 50 across the motor as pointed out hereinbefore, and to this end the switch 35 drops open and a low voltage reverse switch 36 goes in. The closure of this switch 36, which is also an electromagnetic switch, does not alter the polarity on the 55 motor terminals, but merely connects the terminals 1 and 3 of the motor, respectively, with taps 37 and 38 on the transformer 33 through the contacts 39 and 40 of the switch 36 and conductors 41 and 42.

The closure of the main switch 30 also starts 60 all of the individual motors 12 of the tool heads inasmuch as the power for these motors is derived from the lines T¹, T², and T³ through leads HM.

The solenoids (not shown) which control the 65 mechanism effecting the descent and retraction of the tools are also energized by power derived from the lines T¹, T², and T³ through lines HS, but only when a head trip solenoid switch 43 is closed.

The control circuits for the various switches 70 just referred to, and the manner in which they function, will now be described.

Assuming that the tools are up or retracted so that all of the A limit switches are closed, closure 75

of the main switch 30 renders the lines T¹, T², and T³ live and immediately effects energization of a relay 44. The current for energizing the coil of the relay 44 beginning with line T² at the point where this line leads to the head trip switch 43, follows conductor 45 to one side of the coil and from the other side thereof continues through a conductor 46 to a normally closed bridging contact 47 on the head trip switch 43, and from there continues along conductor 48 to the A limit switches and through these switches onto conductor 49 to line T³ at the point this line connects with the transformer.

Concomitantly with the energization of the relay 44, and as result of the closure of its normally open bridging contact 50, the coil of the forward switch 34 is energized to close the switch 34 and connect the motor across the lines for forward operation.

The circuit for energization of the coil of the forward switch 34 is as follows:

Starting at line T³ at the point this line connects with the transformer, the circuit follows conductor 49 through the A limit switches onto conductor 48, one branch of which connects with the now closed contact 50 of the relay 44. From this closed contact 50 the circuit continues along conductor 51 to a normally closed contact 52 of a relay 53, and passing through this normally closed contact continues along conductor 54 to a normally closed contact 55 on the low voltage reverse switch 36 to continue along conductor 56 to one side of the coil. The other side of the coil is connected through a conductor 57 with the conductor 41 which leads to terminal 1 on the motor.

Inasmuch as no potential is now impressed on the motor, the circuit can be continued through the windings of the motor to its terminal 2 which is directly connected with the live line T².

The coil of forward switch 34 having been energized, the forward switch closes and as a result the motor begins to run in a forward direction to advance the turret to its next indexing position.

With the application of potential on the motor, it is necessary to maintain the energizing circuit of the coil of switch 34 through a holding circuit independent of the motor windings. This circuit is completed from live line T¹ through the now closed contact 58 of forward switch 34, part of line 41, conductor 51 to one side of the coil, and from the other side of the coil back to line T³ along conductor 56, etc., in the manner hereinbefore described.

Directly after the forward motion of the turret begins, the snap switch 17 is actuated to reverse the position of its movable contactor 59, this being effected by the depression of its actuator 18 by the plunger carried arm 19 moving in response to the plunger's rise out of the recess 22 in which it was engaged. The contactor 59 of snap switch 17 thus now bridges its common terminal 60 and its terminal 61. Concomitantly with a bridging of the terminals 60 and 61 of the snap switch 17, the coil of relay 53 is energized.

The circuit for energizing this coil, beginning with line T² at the point this line leads to the head trip switch 43, extends along conductor 45 to one side of the coil, and from the other side thereof continues through conductor 63 to the center terminal 60 of snap switch 17, through the snap switch to its terminal 61, conductor 64, normally closed contact 65 of relay 53, conductor 51, to then closed contact 58 of relay 44,

conductor 48, the A limit switches, and conductor 49 back to line T³.

It will be recalled that the holding circuit for the coil of forward switch 34 is completed through the normally closed contact 52 of relay 53, and as this contact opens with energization of the relay 53, means must be provided to prevent the break which would occur in the coil circuit of switch 34 as a result of the opening of contact 52. For this purpose, the normally open contacts 66 and 67 of the relay 53 overlap in their functions with the contact 52 so that these contacts 66 and 67 close prior to the opening of contact 52 to maintain the circuits passing through contact 52.

For instance, the holding circuit for the coil of forward switch 34 instead of passing through contact 52 now continues through that part of conductor 54 which leads to contact 66. This contact being closed, the circuit continues through a branch of conductor 64 which leads to terminal 61 of snap switch 17. From this point the circuit continues through the snap switch to conductor 63 and a branch thereof to the then closed contact 67 of relay 53 which connects with conductor 51 to continue the circuit in the manner aforesaid.

At this point in the operation, relay 44 is energized, relay 53 is energized, and forward switch 34 is closed so that the motor is running in a forward direction advancing the turret to its next indexing position.

It is to be observed that with the change of circuits effected by the energization of the relay 53, the snap switch 17 has been connected in series with the coil of the forward switch 34. Consequently, a subsequent actuation of this snap switch 17 to return its contactor into bridging relation with its terminals 60 and 62 opens the energizing circuit for the coil of the forward switch 34 and causes the forward switch to drop out.

This actuation of the snap switch 17 is effected by spring propelled outward projection of its actuator 18 permitted by the entrance of the plunger 20 into the recess 22 which moves with the turret and reaches the plunger 20 at an instant so timed with the inertia of the parts, that the opening of the forward switch and the closure of the reverse switch 35 to effect plugging of the motor which also follows as a result of this actuation of the snap switch 17, takes place when the turret has advanced a short distance beyond its proper indexed position.

Energization of the coil of switch 35 is effected by closure of the following circuit by the snap switch 17. Beginning with line T³ this circuit continues along conductor 49, through the A limit switches, conductor 48, the closed contact 50 of relay 44, conductor 51, to the then closed contact 67 of relay 53, conductor 63 to terminal 60 of snap switch 17 and passing through contactor 59 of snap switch 17 to terminal 62. The circuit continues along conductor 68, to the then closed contact 69 of relay 53, a conductor 70 which leads to the center terminal 71 of snap switch 25. This snap switch at this time has its contactor 72 engaging its terminal 73 and disengaged from its terminal 74, and as the terminal 73 is connected with one side of the coil of reverse switch 35, the circuit is completed to said side of the coil. From the other side of the coil, the circuit continues through a conductor 75 which leads to conductor 42 and thence to terminal 3 on the motor.

Here, it is desired to note that this manner of electrically interlocking the forward and reverse switches insures against short circuiting as a result of simultaneous closure of both forward and reverse switches. This follows from the fact that the energizing circuit for the coil of the reverse switch cannot be completed through the motor as long as potential is impressed on the motor, either through actual closure of the forward switch 34 or the hanging on of an arc across its contacts. In other words, with this manner of completing the energizing circuit for the coil of reverse switch 35, closure of the reverse switch is positively precluded until the motor is completely disconnected from the lines.

Hence, as soon as any arc hanging on across the contacts of the forward switch 34 is extinguished, conductor 42 assumes the polarity of line T¹ through the windings of the motor to complete the energizing circuit for the coil of reverse switch 35. When this occurs, the reverse switch 35 closes and connects the motor across the lines, but with a reverse polarity, as noted hereinbefore, so that the motor is plugged on full voltage.

With the closure of the reverse switch, the energizing circuit for its coil is completed independently of the motor windings inasmuch as conductor 42 with which one side of the coil is connected through conductor 75 becomes connected with line T¹ through then closed contact 76 of switch 35. The coil of switch 35 is thus connected across lines T¹ and T³.

As soon as the turret begins a retrograde movement, snap switch 25 is actuated to cause its contactor 72 to leave terminal 73 and engage terminal 74. This actuation of the snap switch 25 obviously deenergizes the coil of the reverse switch 35. It also effects energization of the coil of the low voltage reverse switch 36 to connect the motor with the low voltage derived from the transformer 33, but with the same polarity conditions as obtain during the time the reverse switch 35 is closed.

The manner in which this actuation of snap switch 25 effects closure of the low voltage reverse switch 36 is as follows:

Immediately upon engagement of the contactor 72 with the terminal 74, the coil of a relay 77 is energized. Inasmuch as the central terminal 71 of snap switch 25 is connected with line T³ in the manner hereinbefore described, the energizing circuit for the coil of the relay 77 may be traced from the terminal 71 through the contactor 72, to terminal 74 which connects directly with one side of the coil, the other side of the coil being connected through one branch of conductor 51 with conductor 41 which leads to terminal 1 on the motor; and there being no voltage impressed on the motor at this time, the circuit can be completed through its windings to line T¹.

With the energization of relay 77, the coil of the low voltage reverse switch 36 becomes energized. The circuit for this purpose, beginning with line T³, may be traced along conductor 49 and those branches thereof which lead to the relay 77. The contact 78 of this relay now being closed, the circuit continues through conductor 79 which leads to then closed contact 80 of relay 53. Passing through this contact, the circuit is continued through conductor 81, to one side of the coil. The other side of the coil is connected through a conductor 82 with conductor 42 which leads to terminal 3 on the motor, which means

that the circuit is completed through the motor windings to line T¹.

Closure of the switch 36 in response to energization of its coil closes a holding circuit for its coil independent of the motor windings which is established by its contact 40 bridging the gap in conductor 42 which now takes the polarity of line T¹. The holding circuit for the coil of the switch 36 is also now completed independent of conductor 79 leads to the then closed contact 79' of switch 36, the open side of which is connected with conductor 49.

With the closure of the low voltage reverse switch 36, the coil of the head trip switch 43 is connected across lines T² and T³ for energization. Its circuit is as follows:

One side of the coil is directly connected with line T², while the other side thereof is connected with the then closed contact 83 of switch 36 through a conductor 84. From this closed contact 83, the circuit continues along conductor 68 to snap switch 17, conductor 63 to then closed contact 61 of relay 53, conductor 51 to closed contact 50 of relay 44, through the A limit switches, and conductor 49 back to line T³.

With the closure of the head trip switch 43, the lines HS leading to the solenoids which initiate the descent of the tools are energized. It is essential though that the turret be brought firmly against its stop by the motor operating in reverse on low voltage prior to the tools becoming operative. Hence, a sufficient time lag must be provided in the functioning of the mechanism which effects the descent of the tools.

With the closure of the head trip switch 43, its normally closed contact 47 through which the energizing circuit for the coil of relay 44 was completed, opens thus allowing the relay 44 to drop out with the result that its contact 50 opens and its normally closed contact 85 closes. The opening of contact 47 of head trip switch 43, however, lags behind the closure of a contact 86 of switch 43 and the closure of this contact 86 compensates for the dropping out of contact 50 on relay 44 to maintain the relay 53 and the coil of the low voltage reverse switch 36 energized until the A limit switches open.

To illustrate, the energizing circuit for the coil of the relay 53 where it continues along conductor 51 from then closed contacts 67 of relay 53 instead of going down on that branch of conductor 51 which leads to contact 50, now continues upwardly along the opposite branch thereof to the then closed contact 86 which is connected with conductor 48 which in turn leads through the A limit switches to conductor 49 and line T³.

However, as soon as the A limit switches or any one of them opens as a result of the descent or feeding stroke of the tools, the energizing circuits for the relays 43, 53 and 77 are broken, which deenergizes the solenoids of the tool heads, permits normally closed contacts 52 and 65 of relay 53 to reclose, and opens the contact 78 of relay 77. The deenergization of these relays, however, does not entail opening of the low voltage reverse switch 36, as the energizing circuit for its coil is maintained during the turret's period of standstill so as to hold the turret against its stop by the reduced torque of the motor.

The circuit for this purpose, beginning with line 42 which is now live and has the polarity of line T¹, may be traced along conductor 82 to 75

one side of the coil, and from the other side of the coil along conductor 31 and that branch thereof which leads to the then closed contact 35 of relay 44. From the other side of this contact, the circuit is continued along conductor 49 to line T³ entirely independent of the A limit switches.

Hence, at this stage in the operation, only the low voltage reverse switch 36 is closed, and this condition obtains as long as the tools perform their work and until all of the A limit switches are reclosed by the lifting or retraction of all of the tools back to their inoperative positions. When this occurs, relay 44 is again energized.

Energization of the relay 44 now not only initiates the repetition of the entire cycle as in the manner aforesaid by the closure of its contact 50, but in opening its contact 35, it also deenergizes the coil of the low voltage reverse switch 20 36.

All of the instrumentalities are thus in the same positions they were at the initiation of the described cycle; and as will be readily apparent, this same sequence of operations continues as long as 25 the main switch 30 remains closed.

From the foregoing description taken in connection with the accompanying drawings, it will be readily apparent to those skilled in the art, that this invention provides a driving and control mechanism for the turrets of machines of the character described wherein objectionable mechanical expedients for cyclically advancing the turret and holding it at a standstill are obviated; and wherein the initiation of each cycle 35 is directly controlled by the completion of the work being done by the slowest tool so that no time is wasted and greater flexibility of adjustment to different types of work is effected.

What we claim as our invention is:

40 1. In a device of the character described: a member which is to be advanced to a definite predetermined position and there held for a period of time; a reversible electric motor; a positive continuously operative driving connection between the motor and said member through which the motor operating in one direction advances said member forwardly beyond said definite position and operating in the reverse direction imparts retrograde movement to said member; stop means for arresting retrograde movement of said member, said stop means being positioned to accurately define said predetermined position; and means for effecting a reduction in the torque of the electric motor upon retrograde movement of 55 said member so that the electric motor holds said member against the stop means with a reduced torque.

2. In a device of the character described: a member which is to be advanced to a predetermined definite position and there held for a period of time; means for effecting advance of said member forwardly beyond and back to said predetermined definite position; stop means for arresting retrograde movement of said member to accurately define said predetermined position of the member; an electric motor; and a positive and continuously operative driving connection between the motor and said member so that the torque of the motor holds said member against 70 said stop means.

3. In a device of the character described: a member which is to be advanced to a predetermined definite position and there held for a period of time; means for effecting advance of said member forwardly beyond and back to said

predetermined definite position; stop means for arresting retrograde movement of said member to accurately define said predetermined position of the member; an electric energy translating machine; and a positive and continuously operative driving connection between the translating machine and said member so that said member is held against the stop means through the dissipation of electrical energy by the translating machine.

4. In a machine of the character described having a tool positioned at a definite location: a work carrying member movable to position work in operative relationship to the tool; a stop against which the work carrying member is movable to accurately locate the same; an electric motor; and a continuously operative driving connection between the motor and the work carrying member through which the work carrying member is moved into engagement with the stop and there held by the torque of the motor.

5. In a machine of the character described including a movable table: means for indexing the table comprising, a stationary stop for arresting movement of the table; and an electric motor permanently and continuously drivingly connected with the table to bring the table against the stop and hold the same there by the torque of the motor.

6. In a machine of the character described including a movable table: means for indexing the table comprising, a stationary stop for arresting movement of the table; a single electric energy translating machine for imparting a fast initial and a slow final indexing motion to the table; and a positive continuously operative driving connection between the translating machine and the table through which the translating machine drives the table and whereby the table is held against the stop by the dissipation of electrical energy.

7. In a machine of the character described including: a movable table; means for indexing the table comprising a stationary stop for arresting movement of the table; a single electric energy translating machine; a positive continuously operative driving connection between the translating machine and the table through which the translating machine drives the table and whereby the table is held against the stop by the dissipation of electrical energy; and means for effecting a reduction in the potential impressed on the translating machine prior to engagement of the table with the stop so that the table has a slow final indexing motion and is held against the stop by the reduced torque of the translating machine.

8. In a turret structure: a turret to be cyclically advanced and brought to a standstill; drive means for imparting a long advancing and a short retrograde movement to the turret; stop means for limiting retrograde movement of the turret and thereby causing the turret to come to a standstill at a predetermined position at the end of a cycle; an electric motor; and a continuously operative driving connection between the electric motor and the turret through which the motor holds the turret against said stop means by its torque.

9. In a turret structure: a turret to be cyclically advanced and brought to a standstill; stop means for defining the positions of rest for the turret; an electric motor connected with the turret for advancing the same; means to effect plugging of the motor to stop the turret after it has traveled slightly beyond its positions of rest; and

- means for effecting operation of the motor with reduced torque and in a reverse direction to bring the turret against said stop means by retrograde movement of the turret and to hold the turret against the stop means by the reduced torque of the motor.
10. In a device of the character described: a member to be advanced to a predetermined position and there held for a period of time; a reversible electric motor for advancing said member forwardly beyond said predetermined position and retracting it; stop means for arresting retrograde movement of said member and for accurately defining said predetermined position of the member; and control means for plugging the motor to effect retrograde movement of said member and for reducing the voltage across the motor substantially the instant retrograde movement of said member begins, whereby said motor operating with a reduced torque holds said member against the stop means.
11. In a device of the character described: a member adapted to be successively moved to definite positions of rest; a reversible electric motor drivingly connected with said member for successively advancing the same slightly beyond the proper positions of rest and imparting retrograde movement thereto; stop means for arresting retrograde movement of the member at the proper point to accurately define said positions of rest; means for connecting the electric motor with a source of electrical energy to have it run in a direction necessary to advance said member; means controlled by movement of said member to effect plugging of the motor in time to arrest advance of said member at the proper instant to allow for a short retrograde movement thereof into engagement with said stop means; and means controlled by retrograde movement of said member for effecting a reduction of the potential on the motor the instant retrograde movement begins and for maintaining such reduced potential on the motor throughout the entire period of rest of said member so that the motor gently moves said member against the stop means and holds it there.
12. A motor control system of the character described comprising: a reversible electric motor; a forward magnetic switch for connecting the motor with supply lines to effect forward operation of the motor; a reverse magnetic switch for connecting the motor with the lines to plug the motor; a magnetic low voltage reverse switch for connecting the motor with a source of potential less than full line voltage to effect reverse operation of the motor with reduced torque; control circuits for energizing said magnetic switches; and control means in said circuits for successively energizing the magnetic forward switch, the reverse switch, and the low voltage reverse switch, whereby the motor is operated first in a forwardly direction, then plugged, and then is operated in a reverse direction at low voltage.
13. A motor control system of the character described comprising: a reversible electric motor; a forward magnetic switch for connecting the motor with supply lines to effect forward operation of the motor; a reverse magnetic switch for connecting the motor with the lines to plug the motor; a magnetic low voltage reverse switch for connecting the motor with a source of potential less than full line voltage to effect reverse operation of the motor with reduced torque; control circuits for energizing said magnetic switches; control means in said circuits for successively energizing the magnetic forward switch, the reverse switch, and the low voltage reverse switch whereby the motor is operated first in a forwardly direction, then plugged, and then is operated in a reverse direction at low voltage; and an electrical connection between the forward and the reverse switches whereby energization of the magnet coil of the reverse switch cannot take place until the forward switch is completely open and arcing across its contacts ceases.
14. In combination: a turret to be cyclically advanced to a sequence of definite positions; a stationary stop; a stop movable with the turret and engageable with the stationary stop for defining said positions, engagement of said stops requiring retrograde movement of the turret; a reversible electric motor connected with the turret for advancing and retracting the same; means for controlling operation of the motor to effect an advance of the turret slightly beyond said definite positions and for effecting retrograde movement thereof to engage said stops, said means including a magnetic forward switch and a magnetic reverse switch; and control circuits for controlling energization of the magnetic forward and reverse switches, said control circuits being completed through the windings of the motor so that the energizing circuit for one switch cannot be established until the other switch is completely open.
